UNITED STATES PATENT OFFICE.

LAJOS PAP, OF ARAD, AUSTRIA-HUNGARY.

TOOTH-BRUSH.

1,114,646.

Specification of Letters Patent. Patented Oct. 20, 1914.

Application filed December 26, 1912. Serial No. 738,776.

To all whom it may concern:

Be it known that I, LAJOS PAP, a citizen of the Kingdom of Hungary, and resident of Arad, Austria-Hungary, have invented 5 certain new and useful Improvements in Tooth-Brushes, of which the following is a specification.

The present invention relates to improvements in tooth brushes, and more particularly to that type which is provided with a hollow handle that serves for the reception of a tube, containing tooth-paste or other semi-solid dentifrice, the latter being adapted to be fed or forced to the bristles of the brush, whenever it is intended to use the same.

One of the objects of the present invention is to provide means, whereby the outlet in the paste containing tube is maintained 20 in proper alinement with a discharge nozzle in the back or body of the brush, in order that none of the tooth paste may escape into the interior of the brush handle or body and subsequently harden there, causing difficulties in the insertion of fresh tubes.

With these and other objects in view, which will more fully appear as the nature of the invention is better understood, the same consists in the combination, arrangement and construction of parts hereinafter 30 fully described, pointed out in the appended claim and illustrated in the accompanying drawings, it being understood that many changes may be made in the size and proportion of the several parts and details of construction within the scope of the appended claim without departing from the spirit or sacrificing any of the advantages of the invention.

40 One of the many possible embodiments of the invention is illustrated in the accompanying drawings, in which:

Figure 1 is a side elevation of a tooth brush constructed in accordance with the present invention; Fig. 2 is a longitudinal section taken through the tooth paste containing tube; and Fig. 3 is a transverse section taken through the handle of the brush and the tooth paste tube situated therein.

50 Referring now to the drawings, the character *a* denotes the brush handle, provided with the usual back *a'*, into which bristles *j* are inserted in any suitable manner. The

handle *a* is tubular in form, and communicates through a discharge nozzle *b* with the 55 bristles. said discharge nozzle extending substantially at right angles to the face of said back, and being made of rubber or other resilient material to prevent injury to the gums. In the inner face of the rear end of 60 the handle is provided a recess *c*, in which is adapted to be seated a projection *e* of a paste containing tube *d*, when the latter is inserted into the handle. The projection *e*, engaging the recess *c*, firmly holds the tube 65 in the handle against longitudinal movement. The tube *d* is so dimensioned that, when the projection *e* engages in the recess *c*, the outlet *f* in said tube is brought into registering position with the discharge 70 nozzle *b*. Rotation of the tube in the handle is prevented by flattening a portion of the wall of the handle, as clearly shown in Fig. 3 of the drawings, and in a similar manner shaping the paste tube *d*. Within the tube 75 *d* is disposed a screw-threaded spindle *h*, that is provided upon its outer end with a knob *g*, and meshes with the screw threads of a piston *i*, in the form of a nut, which is located within the tube *d* and is formed to 80 correspond with the cross section of the tube, whereby, when the spindle *h* is rotated, the nut cannot turn, but is compelled to advance longitudinally.

In use a portion of the contents of the 85 paste tube may be forced into the bristles, as needed, by grasping the knob *g* between the thumb and finger and turning the same, which imparts a corresponding movement to the spindle and advances the piston *i*, that 90 presses against the body of the contents. A partial turning of the spindle is usually sufficient to deliver a sufficient quantity for use at one time from the contents of the tube through the outlet *f* and the discharge 95 nozzle *b* to the bristles. It is to be observed that the knob *g* is fixedly attached to the spindle *h*, consequently the paste tube with the feeding means, that is to say the piston, knob and spindle, form a unit that can be 100 removed from and inserted, as a whole, into the tubular handle of the brush. Inasmuch as the paste cannot escape into the interior of the brush back or body, the handle will always remain clean and ready for the reception of fresh tubes.

What I claim is:—

In a tooth brush, the combination with a hollow handle provided with a discharge nozzle leading to the bristles, of a paste tube located in said handle provided with an outlet in alinement with said discharge nozzle, means for feeding the contents of said tube through said outlet into said discharge nozzle, and means for fixing the position of

said tube in said handle and thereby maintaining said outlet in registering position with said discharge nozzle.

Signed at Budapest, Hungary, this 16th day of December A. D. 1912.

LAJOS PAP.
